UNITED STATES PATENT OFFICE

DANIEL T. MACLEOD, OF MILWAUKEE, WISCONSIN, ASSIGNOR TO PERFEX CORPORATION, OF MILWAUKEE, WISCONSIN, A CORPORATION OF WISCONSIN

TRANSFORMER COOLER

Application filed March 3, 1928. Serial No. 258,854.

This invention relates to means for cooling electrical transformers and particularly the type in which an oil bath is employed for insulating and cooling the transformer coils.

It is customary to surround transformer coils by an oil bath and to provide external radiator tubes communicating with the transformer housing near the top and bottom whereby the oil contents may circulate on a thermo-siphon principle so as to cool the oil bath by the dissipation of heat to the external atmosphere. Such arrangements are, however, comparatively inefficient because the oil becomes sluggish in cold weather and does not circulate freely and in hot weather the loss of heat is insufficient to prevent an excessive rise of temperature in the bath when the transformer is under load. Such radiators are sometimes arranged to take advantage of the wind by grouping radiator coils or tubes on various sides of the transformer but even under the best of conditions no more than two groups of such radiators will work effectively at one time and since the radiators and housing are subjected to the heat of the sun and the external atmosphere, they have but little cooling effect during extremely hot summer weather.

The main object of this invention is to provide improved means for cooling the oil bath of electrical transformers to maintain the same within predetermined ranges of temperature regardless of load and atmospheric conditions; and to provide an improved apparatus of this type wherein the cooling medium will be circulated mechanically through and exteriorly of the transformer under thermostatic control for automatically adjusting the cooling effect to the load.

These objects are accomplished by the construction shown in the accompanying drawings in which:

Figure 1 is a side elevation of an electrical transformer provided with cooling devices in accordance with the present invention.

Fig. 2 is an elevation of the radiator viewed from the line 2-2 of Fig. 1, the core of the radiator being broken away and indicated only by a fragmentary portion thereof in

order to show the arrangement of the fan and motor at the rear thereof.

In the form shown in the drawings the transformer is provided with an oil tight housing 1 adapted to contain an oil bath in 55 which the transformer coils (not shown) are submerged. This housing is provided with a jacket 2 packed with suitable insulating material 3 for protecting the housing from being heated by the sun or the surrounding atmosphere in hot weather. Heat transfer apparatus preferably in the form of a radiator 4 of automotive type is mounted exteriorly of and preferably at one side of the housing 1 and its upper tank or header 5 is 65 connected with the upper portion of the transformer housing 1 by a pipe 6. The lower tank 7 of the radiator is connected by a pipe 8 with a circulating pump 9 which in turn is connected by a pipe 10 with the lower part 70 of the housing 1. These connections are preferably provided with headers 11 and 12 respectively each having a series of ports in communication with the interior of the housing 1 and its upper tank or header 5. 75

The core 13 of the radiator may be of any usual type; for example, one having vertical passages between the top and lower tanks for circulation of the oil and having transverse air passages.

An electric motor 14 is mounted on the supporting frame and suitably connected with the circulating pump 9 and an exhaust fan 15 for simultaneous operation of said pump and fan. The fan is also surrounded by a fan 85 housing 16 as in certain types of automotive radiators for improving the efficiency of the air flow through the radiator.

The motor is controlled by a switch 17 which in turn is controlled by a thermostat 90 18 having thermal couples or other heat sensitive means extending into the interior of the housing 1 so as to be sensitive to changes in temperature of the oil bath within the housing.

The operation of the device shown is as follows:

The thermostat 18 which may be of any suitable type is constructed or adjusted so as to close the switch 17 connecting the motor 100

14 with its source of power, indicated by the line wires 19, when the temperature of the oil bath is in the vicinity of 140 degrees or such other temperature as may be predetermined and to open the switch when the oil temperature falls, say, for example, 5 degrees below such predetermined temperature. Thus the cooling device will operate intermittently as required, depending upon the 10 electric load on the transformer which tends to heat the oil and the cooling effect of the radiator. It will be understood that the motor under its automatic thermostatic control will operate only to the extent necessary to reduce the temperature of the oil bath to the 15 degree for which the thermostat is set and that, of course, the periods of operation will be longer in the summer when the atmosphere is hot than in the winter, but it is apparent 20 that a single radiator can take care of the entire cooling requirements of a large transformer or of a series or group of transformers which are simultaneously operated.

By reason of the improved cooling effect 25 of the herein described apparatus and the insulation of the housing of the transformer, the oil bath will be protected from excessive heating in summer and excessive cooling in winter and the ideal isothermal condition 30 will be approximated. There will accordingly be less evaporation of the oil, the sizes of the transformer and its housing may be reduced, a cheaper quality of oil may be used, and it will be unnecessary to change the 35 oil with change of season.

Although but one specific embodiment of 40 this invention has been herein shown and described, it will be understood that details of the construction shown may be altered or omitted without departing from the spirit 45 of this invention as defined by the following claims.

I claim:

1. A cooling system for transformers comprising a casing surrounding the transformer and containing a dielectric cooling liquid, a heat insulating jacket for said casing operating to prevent direct and uncontrolled heat exchange between the liquid in said casing 50 and the environment of the casing, a liquid circulating system connected to said casing and communicating with the interior thereof, a radiator embodied in said liquid circulating system and disposed exteriorly of said casing, 55 a pump incorporated in said liquid circulating system to positively circulate the liquid through said system, a fan for impelling a current of air through said radiator, motor means for driving said fan and said pump, 60 and means responsive to the temperature of the liquid within the casing for regulating the operation of said motor means whereby to maintain a predetermined temperature condition in said casing.

- 65 2. A cooling system for transformers com-

prising a casing surrounding the transformer and containing a dielectric cooling liquid, a heat insulating jacket for said casing operating to prevent direct and uncontrolled heat exchange between the liquid in said casing 70 and the environment of the casing, a liquid circulating system connected to said casing and including pipe lines communicating with the upper and lower portions thereof, a radiator disposed exteriorly of the casing and 75 comprising upper and lower tanks connected to said pipe lines and a core interposed between and connecting the tanks and having liquid passages and air passages, a pump incorporated in said liquid circulating system 80 to positively circulate the liquid through said casing, said pipe lines, and through said radiator, a fan for impelling a current of air through the air passages of said core, motor means for driving said fan and said pump, 85 and means responsive to the temperature of the liquid for regulating the operation of said motor means whereby to maintain a predetermined temperature condition in said casing.

Signed at Chicago, Illinois, this 29th day of February, 1928.

DANIEL T. MACLEOD.
